(57) **CLAIM**

The ornamental design for a hanging sign, as shown and described.

DESCRIPTION

FIG. 1 is a frontal perspective view of a first embodiment of a hanging sign showing my new design;

FIG. 2 is a top view thereof;

FIG. 3 is a bottom view thereof;

FIG. 4 is a right side elevation view thereof;

FIG. 5 is left-side elevation view thereof;

FIG. 6 is a top elevation view thereof; and,

FIG. 7 is a bottom elevation view thereof.

The ornamental design which is claimed is shown in solid lines in the drawings. Any broken lines in the drawings are for illustrative purposes only and form no part of the claimed design.
